[57] CLAIM

The ornamental design for a steering wheel, as shown
and described.

DESCRIPTION

FIG. 1 is a front elevational view of a steering wheel
showing our new design.

FIG. 2 is a side elevational view thereof, the opposite
side being a mirror image of that shown.

FIG. 3 is a rear elevational view thereof.

FIG. 4 is a bottom plan view thereof.

FIG. 5 is an enlarged cross-sectional view taken along
line 5—5 in FIG. 1.

FIG. 6 is an enlarged cross-sectional view taken along
line 6—6 in FIG. 5.

FIG. 7 is an enlarged cross-sectional view taken along
line 7—7 in FIG. 1.
